UNITED STATES PATENT OFFICE.

RUDOLPH CONRADER, OF ERIE, PENNSYLVANIA.

REGULATOR.

1,156,392.

Specification of Letters Patent. Patented Oct. 12, 1915.

Application filed November 14, 1910. Serial No. 592,346.

To all whom it may concern:

Be it known that I, RUDOLPH CONRADER, a citizen of the United States, residing at Erie, in the county of Erie and State of Pennsylvania, have invented new and useful Improvements in Regulators, of which the following is a specification.

This invention relates to regulators and consists in certain improvements in the construction thereof as will be hereinafter fully described and pointed out in the claims.

More particularly the invention relates to that type of regulator which is actuated by a pressure device, and the controlling valve of the regulator is usually so connected with either a motor or compressor so that the action upon the controlling valve controls the pressure. With regulators of this type, it is desirable for different purposes to have different actions of the controlling valve under the influence of changes of pressure on the pressure device. That is, for some purposes, it is desirable to have a pressure device which moves the valve gradually with an increase of pressure on the pressure device. While for other purposes, it is desirable to have the controlling device move from one extreme to the other upon certain changes of pressure.

One of the objects of this invention is to arrange the pressure device so that it may be adjusted to operate as desired in this respect.

The invention also involves an improvement in the controlling valve.

The invention is illustrated in the accompanying drawings as follows:

Figure 1 shows a plan view, partly in section on the line 1—1 in Fig. 2. Fig. 2 is a section on the line 2—2 in Fig. 1. Fig. 3 is a section on the line 3—3 in Fig. 1.

1 marks the body of the valve, 2 the diaphragm. The diaphragm is double in form so that there is an outlet, and inlet from it, both top and bottom. Fluid passes through the valve in either direction by the openings 1^a and 1^b.

A bushing 3 is secured in one wall of the diaphragm, and extends through the opposite wall. It has radial openings 4 extending through it between the walls of the diaphragm, and the walls 2^a connecting the diaphragms are of sufficient distance from the bushing 3 to form a passage 2^b so that the fluid can enter or discharge from the bushing in all directions. The valve 5 is of the

rotative type, and is arranged in the bushing, and has radial openings 6 which are brought into and out of register with the openings 4 to open and close the valve. The valve is opened top and bottom so that the fluid passing the valve, enters or discharges both directions of the valve. In this way, the valve is given large capacity, and is balanced.

The valve body is provided with a cover 7, and this cover is secured to the body by the screw 8. A gland 9 is arranged in the cover 7, and the valve stem 10 extends through this gland. The lower end of the valve is squared at 10^a, and extends into a squared socket 5^a in the top of the valve. This is a comparatively loose fit so that the valve can readily find its position without binding of the parts. The upper end of the stem 10 has the squared end 11 on which a crank 12 is arranged. The crank has the throated end 13.

The pressure device is as follows: A cylinder 14 is secured on the bracket 15 extending from the cover 7, and is secured thereon by means of the screws 16. Fluid is pumped to the cylinder through a pipe 17, and, of course, leads from some supply which it is desired to control, ordinarily a receiver. A piston 18 is arranged in the cylinder, and this operates upon the pitman 19, the inner end of which is arranged in a socket in the piston. The pitman has the throated end 20, and the links 21 are arranged each side of the throated end and connected therewith by the pin 22. The links 21 are also connected to an ear 23 extending from the cylinder by means of a pin 24. The pitman engages a lever 25 and is provided with a roll 19^a between the arms of the throated end 20. This roll operates on the lever 25 as the end of the pitman swings under the influence of the links 21. The lever 25 is provided with a cam surface 25^a which may be varied in form to vary the action of the pitman upon it. The lever 25 is pivoted between the ears 26 on the cylinder by means of a pin 27. It has the throated end 28 between the arms of which is arranged a trunnion 29. A link 30 secured between the arms forms the throated end 13 of the crank by means of a pin 31. The opposite end of the link 30 is screw threaded and extends through the trunnion 29 and is secured to the trunnion by means of the nuts 32, on each side of the trunnion. By means

of these, the link can be adjusted to give the valve any desired initial position. The extension 33 is arranged on the lever 25, and is connected with a head 34 by means of a pin 36, the head 34 having the arms 35 extending each side of the extension 33. A pin 37 is screwed into the head and extends through the screw 38. The screw 38 is arranged in a stud or post 39 extending from the cylinder 14. The end of the rod 37 is screw threaded and a nut 40 is screwed onto the rod against the screw 38, and by means of this nut, the initial position of the rod may be adjusted, and the adjustment locked by the jam nut 41. A spring 42 is tensioned between the head 34, and the screw 38. Any desired tension may be given to this spring by operating the screw 38.

It will be observed that as the pitman 19 moves outwardly as the piston moves under the influence of the fluid in the cylinder, the outer end of the pitman operating on the lever 25 and cam 25^a is controlled by the links 21, and swung to a circular path with the pin 24 as a center. In the beginning of this movement, the path of the outer end of the pitman is about in line with the pitman, and the end of the pitman is nearest the pivot formed by the pin 27 of the lever 25. As the pitman moves outwardly, however, its path of movement is deflected more and more from a direction in line with that of the piston, and consequently, there is a greater ratio of movement of the pitman along the lever 25 with a given endwise movement of the pitman as the pitman reaches its outward positions. In the normal use of the regulator but a small part of the possible travel of the piston is necessary. Consequently, the pitman may be adjusted so as to have an initial position as shown in Fig. 1 in which case the ratio of increase in leverage by reason of the moving of the end of the pitman away from the pivot of the lever 25 is but slight. If it is desired to have this leverage increase very rapidly so that, for instance, if it is desired to have the valve completely close when the pressure on the piston reaches a point that will start it, this may be accomplished by adjusting the rod 37 by means of the screw 41 to a position which will bring the initial position of the end of the pitman engaging the lever 25 outwardly from that shown in Fig. 1 so that the continued movement of the pitman will be more abruptly deflected from the line of movement of the piston so that with a given movement of the piston, the movement of the end of the pitman relatively to the pivot 27 is very rapid, and consequently, the leverage will increase more rapidly than the strength of the spring by reason of its compression. In this way, any variation along this line may be secured that may be desired

simply by adjusting the initial position of the end of the pitman. After the lever and pitman are adjusted to the position desired for them, the link 30 may be adjusted so as to give the proper initial position to the 70 valve, and the screw 38 may be adjusted to adjust the tension of the spring 42. Of course where the screw 38 is so adjusted, the nut 40 should be adjusted to compensate for the difference in position of the screw. 75

What I claim as new is:

1. In a regulator, the combination of a controlling valve; a pressure device; a pitman actuated by the pressure device; a pivoted link controlling the path of movement 80 of the end of the pitman; a pivoted lever having a different center than the link operated upon by the pitman, the pitman sliding toward and from the pivot of the lever under the influence of the link and 85 varying the ratio of movement toward and from the pivot of the lever with a given movement of the lever in different parts of the path of the end of the pitman acting on the lever; a connection between the lever 90 and the valve; a counter-pressure device acting on the lever; and means for adjusting the relative initial positions of the pitman and lever to vary the change of leverage on the lever with a given movement of 95 the pitman.

2. In a regulator, the combination of a controlling valve; a pressure device; a pitman actuated by the pressure device; a pivoted link controlling the path of movement 100 of the end of the pitman; a pivoted lever having a different center than the link operated upon by the pitman, the pitman sliding toward and from the pivot of the lever under the influence of the link and 105 varying the ratio of movement toward and from the pivot of the lever with a given movement of the lever in different parts of the path of the end of the pitman acting on the lever; a connection between the lever 110 and the valve; a counter-pressure device acting on the lever; means for adjusting the relative initial positions of the pitman and lever to vary the change of leverage on the 115 lever with a given movement of the pitman; and a device for varying the force of the counter-pressure device.

3. In a regulator, the combination of a rotative controlling valve; a pressure device; a pitman actuated by the pressure device; a pivoted link controlling the path of movement of the end of the pitman; a pivoted lever having a different center than the link operated upon by the pitman, the pitman sliding toward and from the pivot of 120 the lever under the influence of the link and varying the ratio of movement toward and from the pivot of the lever with a given movement of the lever in different parts of the path of the end of the pitman acting 125 130

- on the lever; a link connected to the lever; a crank on the valve connected with the link; means for adjusting the link; a counter-device acting on the lever; and means 5 for adjusting the relative initial positions of the pitman and lever to vary the change of leverage on the lever with a given movement of the pitman.
4. In a regulator, the combination of a 10 controlling valve; a pressure device; a pitman actuated by the pressure device; a pivoted link controlling the path of movement of the end of the pitman; a pivoted lever having a different center than the link operated upon by the pitman, the pitman sliding toward and from the pivot of the lever under the influence of the link and varying the ratio of movement toward and from the pivot of the lever with a given movement 15 of the lever in different parts of the path of the end of the pitman acting on the lever; a connection between the lever and the valve; a counter-pressure device acting on the lever; means for adjusting the relative initial positions 20 of the pitman and lever to vary the change of leverage on the lever with a given movement of the pitman; and means for adjusting the connection between the lever and the valve.
5. In a regulator, the combination of a 25 controlling valve; a cylinder; a piston operating in the cylinder; a pitman actuated by the piston; links pivoted at the side of the axis of the piston, and controlling the path of movement of the end of the pitman; a lever pivoted at the opposite side of the axis of the piston operated upon by the pitman; a connection between the lever and the 30 valve; a spring connected to the lever; means for adjusting the initial position of the lever; and means for adjusting the spring.
6. In a regulator, the combination of a 35 controlling valve body having a double diaphragm with connecting wall; a valve bushing extending from one wall of the diaphragm to the other and spaced from the connecting wall to make a surrounding space around the bushing, said bushing having openings through it; a rotative controlling valve arranged in the bushing and having 40 openings operating in connection with the openings in the bushing; a pressure device; a pitman actuated by the pressure device; a pivoted link controlling the path of movement of the end of the pitman; a pivoted lever having a different center than the link operated upon by the pitman, the pitman sliding toward and from the pivot of the lever under the influence of the link and varying the ratio of movement toward and 45 from the pivot of the lever with a given movement of the lever in different parts of the path of the end of the pitman acting on the lever; a connection between the lever and the valve; a counter-pressure device acting on the lever; and means for adjusting the relative initial positions 50 of the pitman and lever to vary the change of leverage on the lever with a given movement of the pitman.
- In testimony whereof I have hereunto set my hand in the presence of two subscribing witnesses.
